SHACKLE DEVICE

Raymond W. Juengst, New Britain, Conn., assignor to The Fafnir Bearing Company, New Britain, Conn., a corporation of Connecticut

Application August 9, 1932, Serial No. 628,057

8 Claims. (Cl. 267—17)

My invention relates to a means for connecting the frame and spring of an automobile and more particularly to an improved connection involving a so-called anti-shimmy device.

5 It is the principal object of the invention to provide an anti-friction shackle device with anti-shimmy means which will be effective in use, relatively cheap to manufacture, and not likely to get out of order.

10 Other objects and features of invention will be hereinafter pointed out or will become apparent upon a reading of the specification.

In the drawing which shows, for illustrative purposes only, a preferred form of the invention—

Fig. 1 is a fragmentary side view of a frame and spring connected by my improved shackle device and illustrating anti-shimmy mechanism;

20 Fig. 2 is a part sectional view taken substantially on the plane of the line 2—2 of Fig. 1;

Fig. 3 is an inside view in elevation of one of the shackle links shown in Figs. 1 and 2.

In said drawing 5 indicates part of a frame and, as illustrated, is the front or horn end of a 25 frame. The frame is provided with a downwardly extending rigid arm 6 comprising part of the anti-shimmy device to be later described. 7 indicates part of a spring to be shackled to the frame. The frame and spring are shackled to 30 each other through anti-friction bearing means, and in the form shown I provide a pair of shackle links 8—9, each having raceways 10—11 for anti-friction bearing members 12—12. Coacting raceway means are carried by the frame and spring 35 and in the form shown I employ shackle pins 13—14 rigidly secured respectively in eyes of the frame and spring. These shackle pins project beyond the sides of their supporting members and are provided with raceway means for coaction 40 with the anti-friction bearing members 12—12 whereby the frame and spring will be anti-frictionally supported from each other.

In the form shown, the shackle links are duplicates of each other and preferably comprise sheet 45 metal channel shaped members, that is, each link is preferably provided with an upstanding marginal flange 15 which may be continuous so as to provide a very light, yet exceedingly rigid, link. The links may be connected by means of a 50 through bolt 16, and, if desired, spaced apart by a spacer 17 interposed between the two links. The anti-shimmy mechanism cooperates with the lower ends of the links.

In the form illustrated, the lower ends of the 55 links are extended downwardly and are of re-

duced width, as shown particularly in Figs. 1 and 3. Abutment means in the form of a block 16' may be interposed between the links 8—9 and is preferably of a width to be received snugly between the flanges on each channel link so that 60 the flanges assist in supporting the abutment means against rotation. The block 16' may have integral threaded lugs 17'—17' extending through holes such as 18 in each of the links, and nuts 19—19 serve to draw the links toward each other 65 and up against the block 16, or, as specifically shown, against the washers or integral lands 20 thereon.

In order to limit the shackling motion of the shackle, I provide spring means. As illustrated, 70 the block 16' may have a pair of holes 21 extending therethrough for the loose reception of a pair of bolts such as 22. A pair of springs such as 23 may surround the bolts 22 and be interposed between the frame arm 6 and the abutment block 16'. The frame arm may be recessed as indicated at 24, and the abutment block may be correspondingly recessed as indicated at 25 for the reception of the one or more anti-shimmy springs 23. At the opposite side of the abutment 75 block 16 there may be another pair of anti-shimmy springs such as 26 engaging the abutment 16' in recesses such as 27 therein. Each bolt 22 may have an abutment collar 28 thereon adjustably held by a nut 29 for engagement with the opposite ends of the springs 26. Thus, by adjustment of the nut 29, the effective functioning of the springs 23—26 may be altered.

When the device is in use, the normal shackling action of the shackle is resisted in one 90 direction by the springs 23 and in the opposite direction by the springs 26. It is to be noted that, as illustrated, the holes 21 are larger than the shanks of the bolts 22 so as to permit freedom of action during the shackling movement. 95 Since the action of anti-shimmy devices is well known at this time, no particular description of the functioning thereof need be here recited.

While the invention has been described in considerable detail and a preferred form illustrated, 100 it is to be understood that various changes and modifications may be made within the scope of the invention as defined in the appended claims.

I claim:

1. In a device of the character indicated, a 105 frame part having an eye therein, a shackle pin rigidly secured therein and projecting beyond the sides thereof, a rigid arm on said frame projecting downwardly, a spring having an eye, a shackle pin rigidly secured in said eye and projecting 110

- beyond the sides thereof, a pair of shackle links each having bearing raceways at spaced apart points, anti-friction bearing members interposed between said raceways and the projecting ends 5 of said shackle pins, said shackle links being extended substantially beyond said spring eye, an abutment block interposed between said shackle links and rigidly secured thereto substantially at the ends thereof, and spring means at opposite 10 sides of said block, together with means for causing said spring means to cooperate with said downwardly extending arm on the frame for the purpose described.
2. In an anti-shimmy vehicle spring shackle, 15 a pair of separable shackle links having extended ends with an abutment block secured therebetween, each link having a pair of spaced apart raceways for anti-friction bearing members, bearing raceway means to be carried by a vehicle 20 frame and a vehicle spring, anti-friction bearing members interposed between said last mentioned raceway means and the raceways on said shackle links, and anti-shimmy spring means cooperating through said abutment block with a part of 25 the vehicle frame for the purpose described.
3. In a device of the character indicated, a pair of pressed metal channel shaped shackle links having a marginally extending upstanding flange defining the channel shape of said links, 30 anti-friction bearing member raceways in each link at spaced apart points, bearing raceway means to be carried by a frame and spring, anti-friction bearing members interposed between said last mentioned raceways and the raceways of 35 said shackle links, an abutment block interposed between said links and fitting at the ends in channels thereof so as to support the block, means for securing said block rigidly to said links, and means including said abutment block for 40 resiliently limiting the shackling motion of said shackle links.
4. In an anti-shimmy vehicle spring shackle, a pair of shackle links each having spaced raceways for anti-friction bearing devices and each 45 having an extended end, a substantially continuous marginal flange around each link, an abutment block fitting at its ends between the walls of the channel in the extended ends of each link and rigidly secured therein, anti-friction bearing 50 means arranged to be interposed between raceways of said links and a vehicle spring and a vehicle frame, and resilient means cooperating 55
- with said block and a relatively fixed part of said vehicle frame for resisting the free shackling movement of said shackle links.
5. In an anti-shimmy vehicle spring shackle, a pair of pressed metal shackle links detachably secured to each other and having raceway means for anti-friction bearing members, means to be carried by a vehicle frame and a vehicle spring and having raceway means, anti-friction bearing members interposed between said last mentioned raceways and said raceway means of said shackle links, each shackle link being extended downwardly at one end below the lowermost raceway therein, an abutment block secured to said shackle links at said extended ends, and resilient means 80 cooperating with said extended ends and a relatively fixed part of the vehicle frame for retarding the free shackling movement of said shackle links.
6. In an anti-shimmy vehicle spring shackle, a pair of elongated separable shackle links, said links having strengthening flanges thereon, abutment means coacting with said links at one end of said shackle and adjacent said strengthening flanges, means for securing said links and abutment means together, means including anti-friction bearing members for anti-frictionally connecting a vehicle frame to a vehicle spring through the medium of said shackle links, and resilient means for cooperation with said abutment means for limiting the shackling motion of said shackle 85 90 95 100 105 links.
7. As an article of manufacture, a pressed metal shackle link having a raceway for anti-friction bearing members adjacent one end thereof and having a second raceway for anti-friction bearing members intermediate the ends thereof, said link having an integral extension at the other end, each side edge of each link having an integral strengthening flange to reinforce the same substantially throughout its length.
8. As an article of manufacture, a pressed metal shackle link having a raceway for anti-friction bearing members adjacent one end thereof and having a second raceway for anti-friction bearing members intermediate the ends thereof, said link having an integral extension at the other end, each side edge of each link having an integral strengthening flange to reinforce the same substantially throughout its length, said flanges extending around both ends of said link.
